MORITZ SCHENKEL, OF BERLIN-CHARLOTTENBURG, GERMANY, ASSIGNOR TO WESTINGHOUSE ELECTRIC & MANUFACTURING COMPANY, A CORPORATION OF PENNSYLVANIA

ANODE FOR MERCURY VAPOR RECTIFIERS

Application filed July 1, 1929, Serial No. 375,005, and in Germany July 7, 1928.

My invention relates to mercury arc rectifiers and more particularly to means for preventing the formation of harmful deposits on the anode insulators or supporting structure.

In mercury vapor rectifiers, it is known that during the blocking period, that is, the duration of predetermined, high voltage part of the cycle and existing for about two-thirds 10 of the cycle, the so-called cathode evaporation takes place in the neighborhood of the anodes, the products of which deposit principally upon the surface of the anode supporting insulators which serve to lead-in the anodes 15 into the tank. Conducting deposits are thus formed on the insulators, which vary the field distribution near the anode, diminish the creepage paths and even cause occasional electric discharges which may be propagated 20 to the anodes.

The cathode evaporation is further favored by the so-called residual charges, that is, charge-carriers which remain behind, from the current-flow period in which the electric 25 carriers of different signs are segregated, and thus the evaporation can be limited by neutralizing the charge-carriers remaining from the blocking period. The present invention is based on this principle. According 30 thereto, metal surfaces are provided near the insulating surfaces which are to be protected from the befouling deposits, which metal surfaces are capable of neutralizing the residual charges which are present in this 35 region.

In the drawing, the single figure is a sectional view through one of the anode shields of a metal-tank mercury-arc rectifier embodying my invention.

In the drawing, 1 denotes the anode of iron or of graphite, insulated from the rectifier tank by insulators 2 and 3, which are provided with channels and ribs to increase the creepage paths. The upper insulator 3 45 has a relatively wide petticoat 4 which protects the anode against condensed mercury falling from the upper part of the tank. An anode-protecting tube or shield 6 is suspended on the insulator 3 by a holder 5.

Since the products of the cathode evapora-

tion, conveyed by the residual charges, are mainly deposited upon the projecting ribs and in the grooves of the insulators, these places are protected, according to the present invention, by keeping away the residual 55 charge carriers which are still present during the blocking period. For this purpose, a number of metallic surfaces 7, 7a, 8, 8a and 9, preferably in the form of grids, such as cylindrical rings or segments, are arranged 60 in front of the insulators, and said surfaces rapidly neutralize the charge-carriers in their vicinity. For the desired effect, it is advantageous that at least one of the neutralizing 65 surfaces shall be disposed as close as possible to the anode but without being in direct contact therewith, in order that no residual charges may then be able to enter into the space between the neutralizing surface and the 70 anode. The neutralizing surface 9 in the neighborhood of the anode is thus held at such a distance from the anode that this distance falls within the order of magnitude 75 of the dark space.

I claim as my invention:

1. A mercury-arc rectifier characterized by an anode, an anode-insulator above the same and having a lower portion adjacent to the lower end thereof, and a grid structure disposed in spaced relation in front of the lower portions of said insulator and in spaced relation over the joint between the same and the anode, the top of said grid structure terminating at some considerable distance above said joint, and the bottom of said grid structure terminating at some considerable distance below said joint but above the extreme lower end of said anode.

2. A mercury-arc rectifier characterized by an anode, an anode-insulator above the same and having a lower portion adjacent to the lower end thereof, and a conducting grid structure disposed in spaced relation in front of the lower portions of said insulator and in spaced relation over the joint between the same and the anode, the top of said grid structure terminating at some considerable distance above said joint, and the bottom of said grid structure terminating at some considerable distance below said joint but above

the extreme lower end of said anode, said grid structure extending close to, but not into contact with, either said lower end of the anode or said lower portion of the anode-insulator.

3. A mercury-arc rectifier characterized by an anode, an anode-insulator above the same and having a lower portion adjacent to the lower end thereof, and a conducting grid structure disposed in spaced relation in front of the lower portions of said insulator and in spaced relation over the joint between the same and the anode, the top of said grid structure terminating at some considerable distance above said joint, and the bottom of said grid structure terminating at some considerable distance below said joint but above the extreme lower end of said anode, said grid structure extending close to, but not into contact with, either said lower end of the anode or said lower portion of the anode-insulator, the spacing being within the order of magnitude of the dark space.

4. A mercury-arc rectifier characterized by an anode, an anode-insulator above the same and having a lower portion adjacent to the lower end thereof, and a plurality of spaced concentric metal rings surrounding, but not touching, the lower portion of said insulator and extending in spaced relation across the joint between said insulator and the lower end of said anode, said metal rings being close to, but spaced from, the anode-insulator for some considerable distance above said joint between said insulator and said anode, the lowest portion of the innermost ring being at some considerable distance below said joint but above the extreme lower end of the exposed anode-portion.

5. A mercury-arc rectifier characterized by an anode, an anode-insulator above the same and having a lower portion adjacent to the lower end thereof, a tubular anode-shield spaced from the exposed lower end of the anode, and extending above and below the same, and a plurality of spaced concentric metal rings surrounding the lower portion of said insulator and extending across the joint between said insulator and the lower end of said anode, said metal rings comprising portions which are close together at every point between the lateral surface of the exposed anode-portion and the top of the anode-shield, said metal rings being close to, but spaced from, the anode-insulator for some considerable distance above said joint between said insulator and said anode, the lowest portion of the innermost ring being at some considerable distance below said joint but above the extreme lower end of the exposed anode-portion.

In testimony whereof, I have hereunto subscribed my name this 17th day of June, 1929, at Berlin-Siemensstadt, Germany.

MORITZ SCHENKEL.
